UNITED STATES PATENT OFFICE.

MEAD HEDGLON, OF SYRACUSE, NEW YORK.

PORTABLE IRONING MACHINE.

Application filed January 23, 1925. Serial No. 4,262.

To all whom it may concern:

Be it known that I, MEAD HEDGLON, a citizen of the United States, residing at Syracuse, in the county of Onondaga and State 5 of New York, have invented certain new and useful Improvements in Portable Ironing Machines, of which the following is a specification.

This invention relates to improvements in 10 ironing machines, designed particularly for household use, and has for its object to provide a novel, simple and light machine, which is readily portable by the operator, the machine preferably being driven as well 15 as heated by electricity. A further object is to provide an ironing shoe which is formed with an upwardly facing shallow longitudinal trough, in which a padded ironing roll rotates and produces the adhesive 20 friction necessary to effect the ironing and smoothing of the articles, as they are moved over a heated surface of the shoe. In the present case, the ironing roll constitutes the driven member of the machine, which is rotatable in a fixed horizontal plane, by an 25 electric motor, and the shoe is disposed directly beneath and substantially concentric to the roll. The rear side of the shoe is shown pivoted to the frame, in a manner 30 to allow the shoe to be moved bodily, as well as to twist or rotate in a horizontal plane relatively to the axis of the roll. The forward side of the shoe is allowed a certain range of adjustment towards and away from 35 the roll in a vertical plane, for facilitating applying and adjusting the articles, by means of an eccentric mechanism, which is controlled manually by a lever, and with the latter is associated adjustable tension 40 means, by which a variable ironing pressure may be effected and maintained. The arrangement of the pivot and eccentric mechanisms is such that, any inequalities of the ironing roll itself, as well as any variations 45 in the thickness of the articles to be ironed are taken care of by the flexing of the tension means, and also by the floatable nature of the shoe, due to the peculiar arrangement of the shoe's pivot. A particular object of 50 this invention is to provide an ironing machine of the class, which is arranged to be operated and controlled by a person who may sit facing the front side of the machine, instead of having to stand and lean over 55 the machine, as heretofore. And a further object is to provide an ironing machine

whereby certain portions of the articles, such for example, as the cuffs and collar-bands of shirts, as well as circular margins or other portions of dresses or skirts, and the like, 60 may be ironed at the remote open end of the machine, without requiring the whole garment to be passed or fed through the machine.

This invention relates particularly to improvements in the ironing machine shown and described in my pending application filed September 25, 1924, Serial No. 739938.

The various features and parts of the invention will be understood from the detailed 70 description which follows and by reference to the accompanying drawings, in which—

Figure 1 is a top plan view of the complete machine. Fig. 2 is a partial front side elevation and a partial central vertical longitudinal section; the latter being taken on line 2—2 of Fig. 1. Fig. 3 is an enlarged detail view of the clutch that controls the ironing roll. Fig. 4 is a front end elevation with the cover of the gear casing removed; 80 showing the gear train that operates the ironing roll; also showing the eccentric mechanism by which certain movements of the shoe are controlled. Fig. 5 is a broken vertical cross-section taken on line 5—5 of Fig. 2; showing the shoe lowered from the ironing roll. Fig. 6 is a similar view showing the shoe in the ironing position. Fig. 7 is a top plan view of the ironing roll and the shoes; showing the shoe twisted horizontally at an angle to the axis of the ironing roll. And Fig. 8 is a rear-end elevation of the machine.

In the drawings, 2 represents a common wooden base, upon which the combined ironing and driving mechanism is rigidly mounted, and rendered easily portable, as one part. One of the ironing members preferably consists of a heavily padded ironing roll 3, which is driven by a motor 4, the 100 said roll being supported for operation in a fixed horizontal plane, by means of spaced rigid brackets 5 and 6. The other member comprises a trough-like ironing shoe 7, substantially the same length as the roll 3, but 105 being broader and normally projecting beyond the opposite sides of the roll, as shown in Figs. 1, 4, 5, 6 and 7. The trough 7' of the shoe is normally disposed concentric to the roll 3, and may be fluted longitudinally, 110 as shown at 7" in Fig. 5, for increasing the frictional area of the ironing surface, as

well as for ventilating the shoe, by allowing the vapor from the damp articles to escape at the opposite ends of the shoe.

The roll 3 consists of a hollow tubular body 3' having normally open ends, in which are permanently disposed concentric heads 3^a, which are bored out centrally to receive similar shaft-sections 8—8', the latter constituting the axis of the roll 3, the said shafts 10 preferably being rigidly secured to the heads 3^a, by means of pins 8^a. The roll 3 is externally covered by a relatively thick layer of padding, 3^b, for suitably cushioning the roll, as shown in Figs. 2, 4, 5 and 6.

15 The top portion of the bracket 5 comprises a hollow body 5', in which housed a train of gears, by which the power of the motor 4 is transmitted to the roll 3. The brackets 5 and 6 are provided with 20 bottom flanges through which bolts 5^a are driven, for rigidly securing the brackets to the base 2. The gear-train consists of a worm 9, which is rigid on a shaft 9', the latter being journalled in bearings 5^b. Upon the shaft 9' is mounted one member 10, 25 of a clutch, the other member 10' of the clutch being rigid on shaft 4' of the motor.

The worm 9 meshes and drives a relatively large gear 12, which is journalled on 30 a stationary shaft 12', the latter being supported by the casing 5', and also by the cover 5^c of the casing, as best seen in Fig. 2. The gear 12 supports and drives a pinion 13, which meshes and drives a relatively large 35 spur-gear 14, the latter gear being arranged concentric to the roll 3, as shown in Fig. 4. The gear 14 is preferably loosely mounted on the shaft 8, upon which it may idle, when the roll 3 is stationary. The gear 14 40 is arranged to be driven constantly by the motor, and the roll 3 is driven during the ironing operations by a clutch *c*, which comprises the outer end of the hub 14' of gear 14, and the corresponding end of an aligning sleeve 8^b, which is keyed to and is slidable on the shaft 8, as shown at 8^c, in Figs. 2 and 3. The sleeve 8^b is journalled in a bearing 5^e of the cap 5^c, and its outer end is formed with a knob 8^d, by which the sleeve 50 may be moved axially on shaft 8 relatively to the roll 3, for starting and stopping the said roll.

The rear edge of the shoe 7 is pivotally supported by a stationary rod or shaft 15, which passes loosely through, and plays in slots 15' formed in flanges 15^a, of the opposite ends of the shoe, as shown in Figs. 4, 5 and 6. By this construction and arrangement the shoe 7 may be moved forwardly and backwardly as well as circularly on the rod 15'. The ends of the rod 15 extends beyond the ends of the shoe and are disposed rigidly in, and are supported by, integral arms or lugs 5^f and 6' of the brackets 5 and 6, as shown in Figs. 1 and 4. The

upper rear portion of the shoe is formed round, for facilitating the discharge of the ironed articles. The forward edge of the shoe is fitted with a similar shaft or rod 17, whose ends also project beyond the ends of the shoe, and upon these projecting ends are mounted respectively a crank 17', and an operating lever or crank 18, as shown in Figs. 1, 4, 5 and 6. The crank 17' and the lever 18 are formed with similar perforated lobes, as 17^a and 18' (see Figs. 2 and 4), which are engaged by the upper hook-ends of guide-rods 19—19'. Both of the said rods extend downwardly from the lobes and are loosely inserted through perforated extensions 5^x and 6^a of the brackets 5 and 6. The rods 19—19' are similarly threaded intermediate their ends to receive adjusting nuts 20. Between the nuts 20 and the said extensions are disposed similar coil compression springs 21, through which the said rods pass, the said springs being disposed between washers 21'—21^a, as best seen in Fig. 4, in which the full lines show the lever 18 depressed and the springs slightly compressed for lifting, and for holding the forward side of the shoe 7 in the ironing position, shown in Figs. 4 and 6. When the lever 18 is moved to the dotted position shown in Fig. 4 and the full line position shown in Fig. 5, it effects the lowering of the forward side of shoe 7 away from the roll 3, by gravity, as shown in Fig. 5. The perforations of lobes 17^a and 18' are so disposed that when lever 18 is lowered to the full line position shown in Figs. 4 and 6, the points of pivotal contact of the rods 19—19' are moved inwardly past, or eccentric to, the axis of shaft 17, and prevents the accidental release and lowering of the shoe, until the operator swings the lever 18 upwardly, as to the dotted position, shown in Fig. 4 and the full line position shown in Fig. 5. The nuts 20 are employed for regulating the tension of the springs 21, 110 for lifting and for sustaining the load of the relatively heavy shoe, as well as for creating the additional pressure of the shoe against the underside of the roll 3, required for performing the ironing work. When 115 the lever 18 is swung upwardly to the dotted or release position, the rods 19—19' are also lifted thereby sufficiently to relieve the pressure of the nuts 20 against the springs 21. This allows the forward edge of the 120 shoe 7 to gravitate away from the roll 3, as shown in Fig. 5; the extent of this lowering of the shoe being limited by the spacing of the shaft 17 and the perforations of the lobes 17^a in which the rods 19—19' 125 are pivoted. This releasing of the lever 18, also allows the springs 21 to relax and lengthen, but the said springs still continue to support the shoe, when the latter is in the position shown in Fig. 5, and said 130

springs therefore tend to regulate or limit the gravitational travel of said shoe. The lever 18 is provided with a rearwardly facing lug 18^b, which is arranged to engage

- 5 a screw or stud 7^c carried by the shoe, for arresting the releasing movement of the lever, as shown in Fig. 4. The top face of the forward edge of the shoe 7 is normally flat, and to the said edge is detachably
 10 applied, preferably in the same plane, a table 22, upon which the unironed articles may rest while being adjusted and fed towards the roll 3, as shown in Fig. 6. The table 22 is spaced from the shoe by asbestos
 15 or other heat resisting spacers 22', which tend to keep the table cool, and the table is secured to the shoe by bolts 22^a, as shown in Fig. 4.

The medial longitudinal portion of the
 20 shoe 7 is preferably hollow and comprises a heating chamber 7^d, in which is disposed the electric heating element consisting of a horse-shoe shaped part 23, as shown in Figs. 1, 4, 5 and 6, and the said element may be
 25 supplied with current by wires 23' and 23^a.

The heating of the shoe may be controlled by any suitable switch or controlling means (not shown) in a well-known manner. The current for the motor 4, which drives the
 30 ironing roll may also be controlled in any usual manner. The arrows in Figs. 4, 5 and 6 indicate the direction of rotation of the roll 3.

In Fig. 7, the shoe 7 is shown at a slight
 35 angle relatively to the longitudinal axis of the roll 3, and indicates the twisting or movement of the shoe in a horizontal plane. This automatic floating action of the shoe will be appreciated, when it is understood
 40 that at the instant a piece of cloth, as α , is fed into the machine, as shown in Fig. 6, the shoe 7 is shifted forwardly on rod 15, until the rear portion of the trough makes contact with the right underside of the roll.
 45 If the article α is the same thickness throughout, the shoe and the roll will be maintained in substantially normal concentric relation, as shown in Fig. 1. When however, the article α is thicker at, say the

50 left margin, than at the right, the extra thickness at the one end will first cause the corresponding portion of the shoe to be forced forwardly and downwardly, while the opposite end will be practically unchanged, and then when the article reaches the rear side of the trough 7', the thickened end of the article will cause the corresponding portion of the shoe to be moved rearwardly on rod 15, as shown at 7^e in Fig.
 55 7. These forward and backward movements of the shoe, whether the latter is moved bodily, or whether one or the other end only is shifted, is effected by the play of the shaft 15 in the horizontal slots 15' of
 60 the shoe. This floating action of the shoe

during the ironing operations is further facilitated, by the flexible or resilient nature of the supports 21 at the forward side of the shoe, as explained.

My ironing machine is extremely simple, durable and light, and may be produced at comparatively low cost. The novel arrangement and disposition of the floating shoe, the controlling lever and clutch, and the adjustable tension means, by which the raising and lowering of the shoe is effected, and also by which the ironing pressure may also be regulated at will, enables me to provide a light portable device of the class, which may be readily moved from place to place, and may be mounted upon a table, or between tables, or chairs, or other supports during the ironing operations, the said machine being arranged particularly for operation by a person while seated at the front side of the machine, within convenient reach of all of the controlling and operating means.

Having thus described my invention, what I claim, is—

1. In an ironing machine, the combination with a padded ironing roll, and means for driving said roll, of a heated trough-like shoe mounted horizontally below said roll adapted for horizontal movements in different directions by means of horizontal slots formed adjacent its rear edge, tension devices supporting the forward side of said shoe, and an eccentric mechanism adapted to cooperate with said tension devices for moving said shoe upwardly and downwardly relatively to the roll.

2. An ironing machine including a driven ironing roll, a heated concave ironing shoe disposed beneath said roll having horizontally slotted brackets enabling the shoe to twist in horizontal planes, means for moving said shoe towards and away from said roll, means for effecting the floating of said shoe in a horizontal plane relatively to said roll, vertically disposed tension means for effecting the ironing pressure of the shoe against the underside of said roll, and means for varying the said ironing tension.

3. An ironing machine including a driven ironing roll, a heated concave ironing shoe disposed and movable horizontally beneath said roll, tension devices for supporting one side of said shoe, means for increasing and decreasing the tension of said devices, an eccentric mechanism interposed between the shoe and said tension devices adapted for raising and lowering said shoe relatively to the roll, and a platform or table cooperating with a projecting edge of the shoe adapted to support the articles while they are being fed horizontally between the roll and shoe.

4. In an ironing machine, the combination with a frame, a padded ironing roll

supported by the frame, and means for driving said roll, of a heated trough-like shoe pivotally mounted in said frame below said roll adapted to twist in horizontal planes 5 for ironing articles of different thickness, said shoe being provided with means so as to enable the shoe to be swung downwardly out of contact with the roll for applying and adjusting the articles, and tension devices 10 adapted to effect the ironing pressure of the shoe against the underside of the roll.

5. In a portable ironing machine, the combination with an ironing roll rotatable in a fixed horizontal plane, and means for driving 15 said roll, of a heated concave shoe mounted horizontally below said roll, means for pivotally supporting one side of said shoe whereby the shoe is adapted to move forwardly and backwardly as well as to 20 twist in a horizontal plane for ironing articles of different thickness, tension devices for resiliently supporting the other side of said shoe, and a manually operable eccentric mechanism adapted for moving the tension 25 controlled side of said shoe towards and away from the roll and for locking the shoe in the ironing position.

6. In a portable ironing machine the combination with a padded ironing roll, of a 30 heated concave shoe having registering horizontal slots adjacent its rear side, means engaging said slots whereby the shoe may be moved in different directions in a horizontal plane, and whereby the forward side of the 35 shoe may be moved in a vertical arc relatively to the ironing roll, tension devices for resiliently supporting the forward side of the shoe, and cranks pivoted to the ends of the shoe and operatively connected with said 40 tension devices adapted to compress and relax said tension devices for raising and lowering said shoe, said cranks adapted for locking said shoe in the ironing position.

7. A portable ironing machine comprising 45 a heated concave shoe having slotted horizontal bearings at its opposite ends, spaced brackets for supporting the shoe, corresponding portions of said brackets supporting a pivotal member adapted to engage and 50 play in said slotted bearings, whereby the forward side of the shoe may be raised and lowered and said shoe may be twisted or rotated in a horizontal plane upon said member, an ironing roll externally padded 55 rotatable in the concave face of the shoe, said roll being supported by said brackets and adapted to be rotated in a fixed horizontal plane, means for driving said roll, and an eccentric mechanism adapted for raising 60 and lowering the forward side of said shoe and for holding the shoe in ironing contact with the roll.

8. The combination with spaced frame 65 sections connected by a rigid rod, an iron- 130

tor for driving said roll, of a floating heated concave shoe disposed horizontally below said roll, said shoe having horizontal slotted bearings adjacent its rear side through which said rod loosely passes, guide-rods for 70 supporting the forward side of the shoe, tension springs mounted on said rods adapted to normally sustain the weight of the forward side of the shoe, and manually operable means carried by said shoe adapted to 75 cooperate with the said springs for moving the shoe upwardly towards the said roll, and said means being adapted to relax the said springs for effecting the gravitation of the forward side of the shoe from said roll. 80

9. In a portable ironing machine the combination with a frame supporting a pivot rod, a driven ironing roll supported by said frame, and power means for operating the said roll, of a heated trough-like shoe disposed horizontally in said frame beneath said roll and having horizontal slots near its rear side engaged by said pivot rod whereby the said shoe may be moved horizontally as well as towards and away from 90 the bottom side of relatively to said roll, tension devices for resiliently supporting the forward side of said shoe, and means cooperating with said devices for effecting the pressure of said shoe against said roll 95 during each ironing operation.

10. A portable ironing machine including spaced brackets, a stationary rod supported by the brackets, a heated concave shoe disposed horizontally between the brackets, the rear side of said shoe being pivoted by and 100 slidable upon said rod, the forward side of said shoe being provided with means so as to enable the shoe to be swung upwardly and downwardly, an ironing roll for frictionally moving articles to be ironed over the concave face of the shoe, said roll being rotatable in a fixed horizontal plane above said shoe, means for driving said roll, tension means for resiliently supporting the forward side of said shoe, and a lever pivoted to the shoe and eccentrically connected with 110 said tension means adapted to increase and decrease the tension and for effecting the swinging movements of said shoe relatively 115 to the roll.

11. A portable ironing machine including an elongated heated shoe having corresponding horizontal slots adjacent its rear side, spaced brackets for supporting said shoe, said brackets being tied together by a rod that passes loosely through the slots of the shoe, springs for resiliently supporting the forward side of said shoe, an operating lever for raising and lowering the forward side of the shoe, an ironing roll disposed above said shoe, said roll being mounted between 120 said brackets and rotatable in a fixed horizontal plane adapted for frictionally moving articles horizontally over a heated face 125 130

of the shoe, means for driving said roll, and means for starting and stopping the roll.

12. In a portable ironing machine, the combination with a frame comprising spaced brackets, and a rod carried by corresponding portions of said brackets, of a heated trough-like shoe disposed between said brackets, said shoe having similar horizontal slots for pivoting and sliding the shoe horizontally upon said rod, a padded ironing roll mounted between said brackets, above, and being rotatable in, the trough of said shoe, a motor for driving said roll, means for controlling the rotation of the roll, means for moving the forward side of said shoe towards and away from the underside of the roll, and means for varying the ironing pressure of the said shoe against the underside of the said roll.
13. A portable ironing machine comprising a heated concave shoe having registering horizontal slots at its opposite ends, spaced brackets for supporting the rear side of shoe, corresponding portions of said brackets being connected by a rigid rod adapted to slidably engage the slots of said shoe, whereby the forward side of said shoe may be raised and lowered and said shoe may be moved forwardly, backwardly and to twist in a horizontal plane, an ironing roll externally padded rotatable in the concave face of said shoe, said roll being supported by said brackets and adapted to be rotated in a fixed horizontal plane, crank pivotally mounted on the ends of said shoe and rockable relatively to the shoe, tension devices adapted to normally support the weight of the forward side of the shoe, and

means cooperating with said cranks and said tension devices for moving said shoe relatively to the underside of the press roll.

14. In a portable ironing machine the combination with a frame having spaced portions tied by a stationary shaft, a driven ironing roll supported by said frame, and power means for operating the said roll, of a heated trough-like shoe disposed in said frame beneath said roll and having horizontal slots pivotally and slidably supporting the rear side of the shoe upon said shaft, whereby the said shoe may be moved universally in a horizontal plane and its forward side may be swung towards and away from said roll, tension devices for supporting and limiting the swinging movement of the forward side of said shoe, and eccentric means adapted to compress the tension devices for effecting the ironing pressure of the shoe against said roll, said eccentric means adapted to hold the shoe unyieldingly against the under side of the roll during the ironing periods, and for relaxing the tension of said devices for effecting the gravitation of the shoe from said roll at the end of each ironing period.

15. In a portable ironing machine, the combination with a padded revoluble roll, of a heated trough-like shoe disposed horizontally beneath said roll and having horizontal slots near one edge enabling the shoe to twist in horizontal planes during the ironing operations, and means for moving the opposite edge of the shoe towards and away from the roll.

In testimony whereof I affix my signature.
MEAD HEDGLON.
